UNITED STATES PATENT OFFICE

WILLIAM H. BAKER, OF MONTREAL, QUEBEC, CANADA

WARP-STOP MOTION FOR LOOMS

Application filed March 5, 1929. Serial No. 344,235.

The invention comprises various improvements that are applicable to warp stop motions for looms, to warping machine stop motions, and to other like stop-motion mechanisms employed for the discovery of breakage, exhaustion, or undue slackness of a yarn or thread, in connections in which a multiplicity of continuous yarns or threads travel side by side in a sheet or series.

10 The principles and features of the said improvements are applicable in stop-motion mechanisms of the type characterized by the employment of endwise-reciprocated toothed feeler-bars that are arranged to cooperate with drop-wires, which are associated with the individual yarns or threads. As is well-known, it is customary to dispose in two or more rows or banks the detectors or drop-wires which are employed in a warp stop-motion mechanism, and to employ a plurality of toothed feeler-bars, one for each row or bank.

15 The invention comprises improved devices subserving certain functions which are required or are deemed of importance in the case of warp stop-motion mechanisms:—namely, imparting yieldingly to the endwise movable toothed feeler-bars the required reciprocating longitudinal movement; calling 20 into action the power-unshipping or other power-discontinuing appliances; ascertaining the particular toothed feeler-bar which has been arrested in its reciprocating movement by a fallen drop-wire, and thereby revealing the particular bank of drop-wires in 25 which such fallen drop-wire is located; and aiding an attendant to ascertain the particular drop-wire which has changed its position and become engaged with a toothed feeler-bar, thereby to assist in finding the broken or slackened yarn or thread, thus facilitating the work of piecing and thereby repairing a broken yarn or thread, or that of remedying the undue slackness, &c. It comprises, also, 30 an improvement in the means for controlling the position of the retainer by which the ends of the grooved guide-bars for the drop-wires and the toothed feeler-bars are retained within the seats occupied by such guide-bars in the frame-portions of the warp stop-motion

mechanism, while providing for the ready application of the said guide-bars to the said seats, and removal therefrom.

35 The general object of the invention is to provide devices of novel, improved, and practical character and construction, for subserving the various functions which have been mentioned.

40 Illustrative embodiments of the improvements are shown in the accompanying drawings, in which latter,—

45 Fig. 1 shows, mainly in elevation, certain parts of a loom having associated therewith warp stop-motion mechanism comprising the said improvements.

50 Fig. 2, sheet 2, shows on a larger scale, in end elevation, the warp stop-motion mechanism of Fig. 1, omitting the knock-off devices.

55 Fig. 3, sheet 3, is a plan view of the portions of the said mechanism which are at the end represented in Figs. 1 and 2.

60 Fig. 4, sheet 4, is a front elevation of the portions which are shown in Figs. 2 and 3.

65 Fig. 5, sheet 1, is a view in vertical section on approximately the line 5—5, of Fig. 4.

70 Fig. 6, sheet 4, is a view in vertical section illustrating chiefly the wings and one of the wires to which references are made later herein.

75 Fig. 7, sheet 2, is a view of the transmission-plunger to which reference is made herein-after, and certain parts in connection therewith.

80 Fig. 8 is a view in vertical section on line 8—8 of Fig. 3.

85 Fig. 9 is a view in vertical section on line 9—9 of Fig. 2.

90 Having reference, first, to certain well-known parts and features which are shown in the drawings:—

95 The mechanism is constructed in this instance to accommodate six rows or banks of drop-wires 1, 1, Figs. 3, 4, 5, which number frequently is employed in practice. As is well-known, the number varies in different cases. At 2, 2, are the stationary guide-bars upon which the drop-wires are strung by means of slots in the drop-wires, in this instance the upper slots, the said guide-bars

having as usual grooves which are occupied by the reciprocatory feeler-bars 3, 3. See Fig. 5. As usual, the cheeks of the grooved guide-bars have formed therein adjacent 5 their ends in the drawings longitudinally-extending slots 200, Fig. 4, through which project the studs 33, 33, carried by the corresponding ends of the reciprocatory feeler-bars. At 4 is one of the stationary stands 10 which are mounted at opposite ends of the warp stop mechanism upon the loom-frame 41, Fig. 1, the said stands serving to support the opposite ends of the guide-bars. At 15 21, 21, Figs. 3 and 4, are represented the notches which are formed in the top-edges of the side-portions or cheeks of the stationary grooved guide-bars; at 22, 22, are the upstanding teeth between such notches; and at 31, 31, are the notches which are formed 20 in the upper edges of the endwise movable feeler-bars 3, 3, the upstanding teeth between such notches being marked 32, 32. At 5, Figs. 3 and 4, is a warp-support at the front side of the set of guide-bars and feeler-bars, and 25 at 6, Fig. 3, is a warp-support that is located at the rear of the said set. In Fig. 5 the line of the warp yarns or threads is indicated by the line *w*. In the case of a warp stop-motion mechanism like that shown in 30 the drawings, the individual drop-wires, in practice, are hung by means of their lower slots, 12, 12, upon the individual warp-threads intermediate the said warp-supports 5 and 6, so that so long as the warp-threads 35 remain unbroken and at sufficient tension they hold their drop-wires uplifted so as to keep the upper ends of the upper slots 11 above the toothed edges of the guide-bars and endwise movable feeler-bars, leaving the feeler-bars free to move endwise unobstructedly. 40 The interaction in case a warp thread breaks or slackens and permits its drop-wire to descend is as usual, namely: such descent results in the landing of the upper end of 45 the upper slot of such drop-wire within a notch of the corresponding guide-bar, in the path of one of the teeth of the associated feeler-bar, so that such tooth engages with the drop-wire and is obstructed thereby, 50 whereby the endwise movement of the feeler-bars is arrested at an intermediate point in the stroke thereof.

As heretofore in some instances, end-support for the guide-bars is afforded by means 55 of an upstanding lip 7, see more particularly Figs. 2, 3, and 4, in connection with the stationary stand 4. As illustrated the said lip has, as usual in practice, notches constituting seats in which the end-portions of the 60 grooved guide-bars are received as shown in Fig. 4, whereby the guide-bars are kept in upright position properly spaced apart from one another, the guide-bars themselves being formed with notches, as shown in Fig. 65 4, to fit over the bottoms of the notches in

the lip, in order to keep the grooved guide-bars from displacement endwise.

At 8 is a swinging retainer such as heretofore has been employed in the like connection, hung pivotally by means of a pin 9 to the stationary stand 4, which last in this instance has front and rear upstanding portions, or lugs, 42, 42, and an intermediate one, 43, with the latter separated from said front and rear ones by spaces 44, 44, which are occupied by downwardly-extending lugs 82, 82, of the retainer 8, while the pin 9 passes through the interlapping portions or lugs. This pivotal mounting of the retainer, 70 enables the latter, when desired, to be swung inward to carry its cross-bar into retaining position over the ends of the grooved guide-bars as in Fig. 4, to prevent their notched ends from rising out of engagement with lip 7; or to be turned outward so as to carry said cross-bar clear of the said ends and out of the way, in order to permit removal and replacement of the grooved guide-bars. The 75 said cross-bar has notches 81, 81, Fig. 3, at its top side to receive the ends of the guide-bars, for the purpose of supporting the guide-bars temporarily in positions above their normal working positions as sometimes is required.

Referring at this point to my improved 80 means for controlling the position of the retainer, whereby to hold it in its inturned closed position, as in the drawings, overlying the ends of the grooved guide-bars, or, in an outturned position, clear of the guide-bars, 100 as the case may be:—The said means comprises a bolt 45 occupying a recess in the intermediate upstanding portion or lug 43, and backed up by an expanding spring 46 within the said recess, the said spring acting with a 105 tendency to cause the said bolt to project laterally from the mouth of the recess, and beyond the corresponding side of the portion or lug 43, into contact with the proximate side of the adjacent downwardly-extending lug 82 of the retainer. In the said proximate face of the said downwardly-extending lug, a depression 47, Figs. 8 and 9, is made. Such depression is located in a position enabling the spring-projected bolt 45 to enter 110 the same when the retainer 8 is swung inward into its closed position as in the drawings. Through occupancy of the depression 47 by the bolt the retainer is kept in its closed position, but upon applying to the retainer a moderate amount of force tending to turn it outward the bolt will slip out of said recess, permitting the retainer to be swung outward. In the present instance, and preferably, the 115 bolt 45 is in the form of a ball, which has the advantage of working easily in connection with the depression 47, and the surface of the lug 82.

The illustrated train of devices employed 120 for imparting the required endwise recipro-

cating movements to the toothed feeler-bars 3, 3, includes, as in the case of earlier warp stop-motion mechanisms of the same class invented and patented by me, a so-called actuator or vibrator 10 having a reciprocating movement in the direction of the length of the toothed bars given to it. The said actuator or vibrator in this instance is mounted by means of arms 101 and 102, with which it is provided at its opposite ends, upon a shaft 103 that is supported at its front and rear ends in holes in cheeks 49, 49, of stand 4, so that the actuator or vibrator is capable of a swinging reciprocating movement around the axis of the said shaft transversely of the loom; that is to say, in the direction of the lengths of the grooved guide-bars and the feeler-bars.

The said movement is communicated to the actuator or vibrator through the agency of an arm 13, Figs. 2 and 4, that is mounted by means of its hub 131 upon an end-portion of shaft 103 and connected by means of a rod 14 with suitable actuating mechanism, not shown. In this instance, as in the case of the warp stop-motion mechanism presented in U. S. Letters Patent to me granted Jan. 29, 1929, No. 1,700,345, the actuating connections of the actuator or vibrator include a manually-operable clutch-device by means of which operative connection may be established throughout the train of mechanism extending to the actuator or vibrator, to secure the reciprocation of the actuator or vibrator and the toothed feeler-bars, with capacity for disestablishment at will of the connection so as to permit the actuator or vibrator to be actuated manually, as is useful in ascertaining in manner well-known to those skilled in the art the particular drop-wire which has changed its position by reason of yarn-breakage, etc.

The clutch-device that is employed in practice may vary in character, construction, and place of application. The one shown is similar to that of the said Letters Patent comprising a pin 15, slidable vertically in guides at 104, 104, in connection with the arm 101 at one end of the vibrator, and adapted to enter as shown the hole 105 in hub 131 of arm 13.

While the pin occupies the said hole, operative connection exists between the arm and the actuator or vibrator, so that when the arm is vibrated by means of the motion-transmitting connections vibrating movement is transmitted automatically to the actuator or vibrator. If the pin be drawn out of the hole, the operative connection will be broken, thereby rendering the actuator or vibrator free from the motion-transmitting connections, so that automatic transmission of movement to the actuator or vibrator is discontinued for the time being, and making it possible to move the actuator or vibrator manually through using the pin as a handle. By means of such manual actuation of the actuator or vibrator it is possible, after the warp stop-motion

mechanism has operated to bring about stoppage of the loom automatically, to work by hand the toothed feeler-bars to aid in determining which row or bank contains a drop-wire which has dropped in consequence of 70 breakage of a yarn or thread, and in finding such drop-wire and the broken or slackened yarn or thread.

The mechanism includes, in combination with the reciprocatory feeler-bars 3, 3, a series of fingers 16, 16, which are mounted in manner providing for swinging movement thereof in the direction of the length of the feeler-bars; and includes also wings 18, 18, which are mounted in manner providing for 80 swinging movement in such direction.

In carrying the invention into effect and as one portion thereof, I adapt fingers 16, 16, to constitute visible indicators serving as guides to aid in ascertaining the row or bank of drop-wires in which a dropped drop-wire obstructs the reciprocatory movements of a feeler-bar; and also to provide means for manual actuation of the individual feeler-bars for finding purposes. Preferably, the said fingers are employed as in the case of spring-members of the prior art, for transmitting yieldingly power from the vibrating actuator or vibrator to the reciprocatory feeler-bars to cause reciprocating movements of the latter; although, in some cases, they may not have this function, which then may be subserved by the wings. The wings 18, 18, are so combined, etc., as to serve to bring the knocking-off devices of the loom into action, in order to discontinue the working of the loom, in case a moving feeler-bar is arrested by a dropped drop-wire. The wings in the case of the illustrated mechanism assist in imparting the required reciprocatory feeling movements to the feeler-bars. As just indicated, in some cases, the said movements may be imparted by means of wings without assistance from fingers such as 16, 16. In such cases the fingers will or may be utilized for manually moving the feeler-bars individually, and/or as indicators, or they may be dispensed with.

In the illustrative embodiment the fingers 16, 16, are carried by the actuator or vibrator, as usual in the case of the spring-elements heretofore; they are flexible; and they are engaged with the studs 33, 33, of the feeler-bars. Thereby, as the actuator or vibrator swings about the axis of shaft 103 the fingers operate to transmit force yieldingly from the actuator or vibrator to the feeler-bars, to move the latter back and forth endwise, and so that the feeler-bars normally are moved in unison, but in case one of them encounters a dropped drop-wire, it may be arrested individually. In the illustrative embodiment the fingers 16, 16, are constituted of lengths of spring-wire, and, in order to be 130

actuated by the actuator or vibrator 10, for the actuation of the feeler-bars, are combined with the actuator or vibrator through being attached at their lower ends to the body of the actuator or vibrator. The mode of attachment, and also the constructive details of the actuator or vibrator, may be varied more or less in practice, as found desirable. In the drawings the said body of the actuator or vibrator is constituted by a cross-bar intermediate the arms 101 and 102, which are sleeved upon the shaft 103. The said cross-bar is located below shaft 103 in order to afford opportunity for employment of fingers 16, 16, of considerable length, so as to attain a more advantageous flexibility accompanying adequate strength. For the attachment of the fingers to the actuator or vibrator, the cross-bar of the latter is provided in this instance with holes which are occupied by the attaching ends of the fingers, and within which the fingers are secured by means of clamping screws 161, 161, Figs. 4 and 5. Removal and replacement of the fingers are accomplished readily. The connection of fingers 16, 16, with the reciprocating feeler-bars is accomplished in the present instance through making the studs 33, 33, with diametrical holes 331 (shown best in Fig. 6) and causing each finger 16 to occupy the hole 331 of the corresponding feeler-bar. Holes 106, Fig. 6, in shaft 103 permit the fingers to extend diametrically through the said shaft, the said holes being enough larger than the fingers to permit free lateral play of the fingers relative to the shaft as the fingers are caused to vibrate in actuating the feeler-bars, and also when they become flexed in consequence of arrest of endwise movement of the feeler-bars by dropped drop-wires.

With respect to visual indication, it will be observed that in the mechanism that is shown in the drawings the upper extremities of the fingers 16, 16, extend sufficient distances above the guide-bars and feeler-bars to cause them to stand up in full view, so that the positions of the respective fingers will be exposed clearly, and so that any departure of one finger from series-alinement with the others, due to obstruction of the movement of its associated feeler-bar by a dropped drop-wire, will be plainly evident. This marks easy the work of finding in well-known manner, through manual actuation of the actuator or vibrator while the mechanism is at rest following stoppage, the row or bank of drop-wires in which a dropped drop-wire obstructs a feeler-bar. Also, the upstanding upper extremities of the fingers are adapted to be grasped as convenient finger-holds, and to be used in manipulating a particular finger and its feeler-bar for finding or other purposes capable of being subserved through manually applying force tending to move the individual feeler-bar endwise.

Referring, now, to the wings 18, 18:—

There is a pair of the said wings, (see more particularly Figs. 3, 5, and 6,) and the two wings composing such pair coact with the studs 33, 33, projecting from the feeler-bars. For such coaction, projections from the tops of the respective wings are arranged to engage with the said studs, those of one wing engaging the studs at the outer side of the latter and those of the other wing engaging the studs at the other side thereof, so that the studs intervene between the engaging portions of the two wings. The wings might be arranged and combined to cooperate with other parts in connection with the feeler-bars, with the same general results. While the parts continue to work normally, the wings and the studs move in unison in the directions in which the feeler-bars are reciprocated. In this instance, the wings are arranged to swing, by reason of being mounted pivotally upon the supporting shaft 103 of the actuator or vibrator by means of lugs 181, 181, of the wings, such lugs having therein holes which fit the said shaft with freedom sufficient to permit the wings to turn relative to the shaft.

The wings are kept in closed relations with respect to the studs 33, 33, of the feeler-bars by means of a controller 19 having a V-shaped notch, Figs. 3 and 7, which is occupied by ears 182, 182, of the wings, as shown best by such views. The inclined side-walls of this notch engage with the exteriors of the said ears, which usually are correspondingly inclined, as in the drawings, to fit the said inclined side-walls. The controller is actuated by spring-pressure to cause such inclined side-walls to act upon the exteriors of the ears with a tendency to press the wings toward each other and thereby hold the ears in contact with each other and the wings in contact with or close to the opposite sides of the studs 33, 33.

In order to cause the wings to swing in synchronism with the actuator or vibrator the controller 19 is mounted to swing in unison with the latter. In this instance it is mounted upon the arm 102 thereof. The form, etc., of the controller may be varied in practice but advantageously it is constituted in the mechanism shown in the drawings of a plunger having a rod-like stem, and is mounted upon the said arm 102 by means of guides which are provided in connection with the arm and in which the said rod-like stem is confined. One of the guides is constituted by an ear 20 on the arm 102 having therein a hole that is occupied by the lower portion of the stem; another is constituted by a pair of grooved guide-rolls 201, 201, between which the portion of stem adjacent the notch is confined.

The spring-tension by which the notched portion of the plunger is held in engagement

with the ears of the wings may be variously applied according to the specific construction that is adopted in the case of the mechanical details. In this instance it is transmitted 5 to the plunger through the agency of a spring-actuated rocker 24, which is mounted between the branches of a forked bracket 25 projecting from one of the cheeks 49 of stand 4, upon a pin 26 extending transversely from 10 one branch of said bracket to the other. A spiral spring 261 acts expansively against an arm 243 of the said rocker, with a tendency to turn the rocker around pin 26 so as to cause an arm 242 of the rocker, through pressure 15 against the lower end of the plunger, to urge the plunger endwise so as to cause the branches of its fork to act upon the ears of the wings with a tendency to press the wings toward each other. The point of contact 20 between the arm 242 of the rocker and the lower end of the plunger 20 is located in line with the longitudinal axis of the shaft 103, in order that the working relations between the said arm and the said lower end 25 may not be disturbed by the swinging of the actuator or vibrator, notwithstanding the fact that the rocker is mounted upon a stationary bracket. Hence the relations between the plunger-end and arm 242 of the rocker, and the effect of the spring in tending to move the plunger endwise, are not affected by swinging movement of the actuator or 30 vibrator.

From the foregoing description it will be understood that when the actuator or vibrator is caused to swing around the axis of shaft 103, the wires 16, 16, and the wings 18, 18, will have swinging movement transmitted to them from the actuator or vibrator, 35 causing them to swing in unison with the actuator or vibrator. Preferably, the power of the spring-tension of wires 16, 16, will be proportioned to enable such wires to take the main burden in actuating the feeler-bars, in 40 which case the tension and effect of the spring 261 will be made just sufficient to cause the wings to retain close relationship to the studs 33, 33, of the feeler-bars as the feeler-bars reciprocate. Or, the conditions may be 45 reversed so that the wings shall take the main burden in communicating the reciprocating movements to the feeler-bars, and the wires shall serve chiefly as indicators.

In case a feeler-bar should be arrested in its movement in either direction by a dropped drop-wire, such arrest taking place at an intermediate point in such movement, it will prevent the associated finger 16 from movement further in such direction, and also arrest the wing which is following behind the studs 33, 33. In consequence, the ear 182 of the arrested wing will become stationary. Further movement of the actuator or vibrator will cause the wire 16 to flex, and in addition

will cause the inclines of controller 19 which is pressing against the ear of the wing that is thus held stationary to slip upon such ear, impelling the controller 19 lengthwise downward. Thereby by reason of such movement of the controller lengthwise the controller will be caused to act against arm 242 of rocker 24 to turn the latter.

The turning movement of the rocker, just referred to, is made instrumental in causing the driving power of the loom to be knocked off. For knocking-off purposes, the arm 241 of the rocker is combined operatively with knocking-off devices whereby such knocking-off is accomplished. As will be apparent, 70 the controller 19 constitutes a slip-coupling or give-away member in causing the wings to move in unison with the actuator or vibrator, and in permitting a slip to take place as a result of further movement of the actuator or vibrator while a wing is held from accompanying the actuator or vibrator. It acts also as in the case of other give-away devices of warp stop motions to bring about the knocking-off action of the knocking-off devices.

Inasmuch as the devices comprising the drop-wires, feeler-bars, actuator or vibrator, &c., including the rocker 24, are located near the rear of the loom in which they are employed, whereas the knocking-off devices are located at the front in the loom, I employ by preference a flexible transmitting means for connecting the first-mentioned devices with the knocking-off devices, thereby simplifying the connections and giving more latitude in respect of the form, location, and arrangement of the knocking-off devices. The said flexible transmitting means may vary in specific character. Thus the well-known Bowden wire may be employed, it comprising a transmission wire combined with a tubular sheath within which it fits with freedom of movement lengthwise. When pushed lengthwise within the tube the transmission wire will be guided by the tubular sheath so as to transmit movement to a part or device located at the far end of the tubular sheath. As is well known, the transmission wire in some instances is utilized through being pulled lengthwise within the tubular sheath. Preferably, I employ an improved construction of flexible transmitting means comprising, instead of the plain wire heretofore used a wire formed into a close spiral resembling a close spiral spring. In Figs. 1 and 5, such a transmission spiral is shown at 27. The containing tubular sheath is indicated at 28. Owing to the multiplicity of gears and other moving parts adjacent the vicinity of the flexible transmitting means, I prefer to employ a rigid tubular sheath as illustrated, formed of metal adapted to be easily bent into the desired relation with the other loom 130

parts. This arrangement prevents the flexible transmitting means from being brought into range of and being broken or damaged by such moving parts, as has frequently happened hitherto, as a result of vibration or of the weaver's efforts to clean around these parts. The continuous spiral transmission member 27 works better than a plain wire in movement within bent portions of the tubular sheath. One end of the transmission spiral is joined by means of a connector 29 to the arm 241 of the rocker 24, so that when the rocker is rocked through the interaction of a temporarily stationary wing and the controller, as just explained, the swinging movement of the arm 241 moves the transmission spiral lengthwise within the tube to bring the knocking-off devices into play. It is feasible to arrange so that this rocking movement of the rocker may result in pushing the flexible transmitting means lengthwise within the tubular sheath, but in this instance the parts are arranged and combined so that the rocking of the rocker acts to pull the flexible transmitting means. The connector 29 is made of wire, with one portion thereof bent to form a hooked end which is engaged with arm 241 by being placed in a hole in the latter. The connector is engaged with the transmission spiral through having its stem screw-threaded and screwed into the central opening extending lengthwise through the spiral. This provides a positive inseparable union of the connector with the transmission spiral. The screw-threaded stem may be screwed readily into the spiral but cannot be pulled out or unscrewed. This safeguards against accidental disengagement. A connector 30, in similar screw-threaded engagement with the other end of the transmission spiral, unites the latter end to the knocking-off devices.

The knocking-off devices may be variously constituted, arranged, &c., in practice. In Fig. 1 of the drawings they comprise a dagger 31 having the forward end of the transmission spiral joined to an upstanding arm thereof, a dagger-support, which is mounted pivotally at 321 upon the loom-frame with capacity to swing rearward and forward and upon which the dagger is mounted pivotally at 311 with capacity to swing in a vertical plane, a rod 313 extending from the dagger-support 32 forward to the neighborhood of the loom breast-beam, a knocking-off lever 34 that is mounted pivotally at 341 upon the loom-frame, with the forward end of rod 313 engaged with one arm thereof and a second arm arranged to engage with shipper-handle 35 for knocking-off purposes, and a bunter 36 that is carried by the lay 37.

These knocking-off devices are of one of the well-known types. The mode of operation thereof is as usual, viz: Normally, the

dagger 31 occupies a position clear of the path in which the bunter 36 moves as the lay makes its strokes rearward. When, however the transmission device is actuated to swing the engaging portion of the dagger into the said path, the lay-carried bunter 36 takes hold thereof in the next stroke of the lay rearward, and drives the dagger and dagger-support ahead of it so as to actuate the knocking-off lever 34 to knock off the shipper-handle 35.

What is claimed as the invention is:

1. The combination with longitudinally reciprocable feeler-bars having projections with holes therethrough, of a vibrator, and flexible fingers extending through said holes and transmitting movement yieldingly from the vibrator to the individual feeler-bars.

2. The combination with longitudinally reciprocable feeler-bars having projections with holes therethrough, of a vibrator, and fingers constituted of lengths of spring wire extending through said holes and through which the vibrator yieldingly transmits movement to the individual feeler-bars.

3. The combination with longitudinally reciprocable feeler-bars, and a vibrator, of flexible fingers through which the vibrator yieldingly transmits movement to the feeler-bars in the direction of the length thereof, with extensions of said fingers projecting into full view some distance above their connection with the feeler-bars, constituting visible indicators of the positions of the respective feeler-bars and finger-holds by which the fingers may be manipulated to work the feeler-bars for finding purposes.

4. The combination with longitudinally reciprocable feeler-bars having projections with holes therethrough, of a vibrator, and fingers constituted of lengths of spring wire extending through said holes and by means of which the vibrator yieldingly transmits movement to the individual feeler-bars, the upper extremities of the said wires extending some distance above the said projections and constituting visible indicators of the positions of the feeler-bars.

5. The combination with longitudinally reciprocable feeler-bars, and a vibrator, of flexible fingers constituted of lengths of spring wire fixedly attached to the vibrator, in operative engagement with the feeler-bars to transmit yieldingly to the feeler-bars force tending to reciprocate them individually, with extensions of the respective wires rising into full view above the feeler-bars to constitute visible indicators of the positions of the respective feeler-bars.

6. The combination with reciprocable feeler-bars, means for yieldingly reciprocating the same, and wings having movements synchronizing with those of the feeler-bars, and a device operatively combined with

the wings and through arrest of a wing due to arrest of a feeler-bar influenced to transmit an indicating action.

7. The combination with a series of reciprocable feeler-bars, and a vibrator from which reciprocating movements are imparted yieldingly to the individual feeler-bars of the said series, of wings having movements synchronizing with those of the series of 10 feeler-bars, and a controller which through arrest of a wing due to arrest of a feeler-bar is influenced to transmit an indicating action.

8. The combination with reciprocable 15 feeler-bars, and a vibrator, of fingers actuated by said vibrator and operating to yieldingly actuate said feeler-bars, wings having movements synchronizing with those of the vibrator, fingers, and feeler-bars, and a controller 20 operatively combined with the wings and through arrest of a wing due to arrest of a feeler-bar influenced to transmit an indicating action.

9. The combination with reciprocable 25 feeler-bars, and a vibrator from which such feeler-bars derive yielding actuation, of wings coordinated with said feeler-bars and normally moving in company with the series thereof, and a controller vibrating in unison 30 with the vibrator, operatively combined with the wings, and through arrest of a wing due to arrest of a feeler-bar influenced to transmit an indicating action.

10. The combination with reciprocable 35 feeler-bars, and a vibrator from which such feeler-bars derive yielding actuation, of a pair of wings coordinated with said feeler-bars and normally moving in company with the series thereof, and a controller vibrating 40 in unison with the vibrator, operatively combined with the wings in manner whereby when either wing is arrested through arrest of a feeler-bar the controller is influenced to transmit an indicating action.

45 11. The combination with reciprocable feeler-bars, and a vibrator, of a pair of vibratory wings coordinated with said feeler-bars, and a controller carried by the vibrator, operatively combined with the wings in 50 manner whereby when either wing is arrested through arrest of a feeler-bar the controller is influenced to transmit indicating action.

12. The combination with reciprocable 55 feeler-bars, and a vibrator, of a pair of vibratory wings coordinated with said feeler-bars, and a controller moving in company with the vibrator, having a cam-engagement with the wings whereby when either wing is arrested through arrest of a feeler-bar the resulting cam-action influences the controller to transmit indicating action.

60 13. The combination with reciprocable feeler-bars, and a vibrator, of a pair of vibratory wings coordinated with said feeler-bars, and a controller moving in company 65

with the vibrator, having a V-notch occupied by projections from the wings, whereby when either wing is arrested through arrest of a feeler-bar the resulting cam-action influences the controller to transmit indicating action. 70

14. The combination with reciprocable feeler-bars, and a vibrator, of a pair of wings coordinated with said feeler-bars, a controller engaged with said wings and vibrating in unison with the vibrator, a spring-actuated 75 rocker cooperating with said controller, and stop-motion connections through which said rocker brings about power-disconnection when arrest of a wing due to arrest of a feeler-bar actuates the controller to rock the 80 rocker.

15. The combination with a plurality of feeler-bar-supporting guide-bars, and a support for the ends of said guide-bars, of a swinging retainer mounted with capacity to 85 be swung into guide-bar-retaining position over the guide-bars and to be swung into position to clear the guide-bars, said retainer having a bolt-receiving depression in a side-surface thereof, of a spring-actuated bolt 90 held pressed by its spring against the said side-surface of the retainer and projected by the spring into the said depression when the latter arrives in line with the bolt. 95

16. In stop-motion mechanism, the combination with detectors, and power-disconnecting means, of transmission means intermediate said detectors and said means, comprising a rigid tubular sheath, a flexible transmitter consisting of a close coil of wire 100 extending through said sheath and freely movable longitudinally therein, and a connector combined with the end of the flexible transmitter by means of a screw-threaded stem screwed into the end of the flexible 105 transmitter and held by engagement of the stem threads between the coils of the wire forming the transmitter. 110
